AIR DRYER JACKET FOR UNDERGROUND
ELECTRICAL CABLE

Thurman A. Pelsue, 3906 S. Hibiscus Way, Denver, Colo.

Filed July 26, 1965, Ser. No. 86,287

Term of patent 14 years

(Cl. D62—1)

FIG. 1.

FIG. 2.

FIG. 3.

FIG. 4.

FIGURE 1 is a front elevational view showing my air dryer jacket for underground electrical cable mounted in place on an electrical cable, the latter having been shown in dotted lines for illustrative purposes only;

FIGURE 2 is a top plan view thereof;

FIGURE 3 is a bottom plan view; and

FIGURE 4 is a section taken along line 4—4 of FIGURE 1.

I claim:

The ornamental design for an air dryer jacket for underground electrical cable, as shown and described.
